CLAIM

The ornamental design for shears, as shown and described.

DESCRIPTION

1.1 Shears

1.1 : Perspective

1.2 : Perspective

1.3 : Left

1.4 : Right

1.5 : Front

1.6 : Back

1.7 : Top

1.8 : Bottom

A handle for clippers or shears is claimed; features shown in broken lines form no part of the claimed design.
